US0D1106724S

(12) **United States Design Patent** (10) **Patent No.:** **US D1,106,724 S**
(45) **Date of Patent:** **** Dec. 23, 2025**

(54) **SANITIZING MAT RACK**

(71) Applicant: **Daniel Bouzide**, Troy, MI (US)

(72) Inventor: **Daniel Bouzide**, Troy, MI (US)

(**) Term: **15 Years**

(21) Appl. No.: **29/887,419**

(22) Filed: **Mar. 21, 2023**

(51) **LOC (15) Cl.** **20-02**

(52) **U.S. Cl.**

USPC **D6/672**; D6/681

(58) **Field of Classification Search**

USPC D19/80; D20/10, 39, 41, 42; D6/310, D6/515, 671.1, 672, 681.1

CPC G09F 7/00; G09F 7/18; G09F 2007/1834

(57) **CLAIM**

The ornamental design for sanitizing mat rack, as shown and described.

DESCRIPTION

FIG. 1 is a perspective view of a sanitizing mat rack; FIG. 2 is a front view of that depicted in FIG. 1; FIG. 3 is a back view of that depicted in FIG. 1; FIG. 4 is a top view of that depicted in FIG. 1; FIG. 5 is a bottom view of that depicted in FIG. 1; FIG. 6 is a right side view of that depicted in FIG. 1; FIG. 7 is a left side view of that depicted in FIG. 1; and, FIG. 8 is a perspective view of that depicted in FIG. 1 with a mat shown for context.

The broken lines in FIG. 3 illustrate portions of the mat rack. The broken lines in FIG. 8 illustrate a mat for context of placement; all broken lines form no part of the claimed design.

1 Claim, 4 Drawing Sheets
